United States Patent Office

Des. 229,068
Patented Nov. 6, 1973

229,068

STEREO SPEAKER

Dennis L. Engle, 9651 Angleridge, Dallas, Tex. 75238

Filed July 9, 1971, Ser. No. 161,431

Term of patent 14 years

Int. Cl. D14—01

U.S. Cl. D26—14 G

FIG. 1

FIG. 2

FIG. 3

FIG. 4

FIG. 1 is a top plan view of a stereo speaker, showing my new design, the bottom being substantially a mirror image thereof;

FIG. 2 is a front elevational view;

FIG. 3 is a rear elevational view; and

FIG. 4 is a right side elevational view, the left side being substantially a mirror image thereof.

I claim:

The ornamental design for a stereo speaker, substantially as shown and described:
